UNITED STATES PATENT OFFICE

BENJAMIN Z. McCAIN, OF OAK PARK, AND HERBERT L. THOMPSON, OF ELGIN, ILLINOIS, ASSIGNORS TO ADDRESSOGRAPH COMPANY, OF WILMINGTON, DELAWARE, A CORPORATION OF DELAWARE

EJECTOR FOR ADDRESSING AND OTHER MACHINES

Application filed March 14, 1928. Serial No. 261,608.

This invention relates to ejectors for discharging the work from an addressing or other machine for which the invention is or may be adapted and its object is to provide 5 an ejector of simple construction which will operate efficiently to discharge the work quickly and immediately after the printing or other operation of the machine is completed.

10 In addressing machines it is desirable to provide as much time as possible for feeding the envelopes or other articles to be printed into printing position, and this makes it likewise desirable to discharge the envelop quickly as possible after it has been printed. This 15 is true with respect to printing machines in general, folding, sealing and other machines for which the invention is adapted. Therefore, it is a prime object of the invention to 20 provide quick acting means which operate immediately after the printing operation is completed for ejecting the work from the machine in a snappy movement.

The invention also has for its object to 25 provide a pneumatically operated ejector which is simple in construction, comprises but few parts and which can be easily applied to a machine without involving much, if any, change in the standard construction thereof.

30 And a further object of the invention is to provide an ejector which can be easily and quickly adjusted for ejecting the work at either side of the machine.

In the accompanying drawings we have 35 chosen a simple form of power operated addressing machine merely to illustrate the invention and without any intention of limiting or restricting the invention thereto, and referring to the drawings,

40 Fig. 1 is an elevation, partly in section, showing parts of a power operated addressing machine with our invention applied thereto.

Fig. 2 is a transverse sectional view on the 45 line 2—2 of Fig. 1.

Fig. 3 is a detail sectional view on the line 3—3 of Fig. 1.

Fig. 3^a is a plan view of a part of the addressing machine showing the invention 50 thereon.

Fig. 4 is a perspective view of a part of the invention.

Fig. 5 is a sectional view on the line 5—5 of Fig. 3.

Referring to the drawings 6 designates 55 generally the frame of the machine, 7 is the platen, 8 is the stamper arm pivoted on the frame at 9 and 10 is a stack of printing devices in a magazine 11 and adapted to be fed one at a time to printing position by suitable 60 means, not shown.

A rocker 12 is pivotally mounted at 13 on the frame of the machine and is oscillated by any suitable power means, or by a foot pedal. An arm 14 is pivoted at 13 and carries a cam 65 15 which engages a roller 15' on the lower end of the stamper arm 8. A spring pressed pawl 16 on the rocker 12 normally engages the arm 14 to cause this arm and the stamper arm to operate at each operation of the 70 rocker, but a release device 17 connected with the selector mechanism of the machine is adapted to depress the pawl 16 whenever a printing device is to be skipped to prevent the pawl from operating the arm 14 and the 75 stamper arm while this printing device is passing through printing position. This structure is commonly employed in certain types of addressing machines and further description thereof is unnecessary.

An air pump 18 is detachably secured by set screws 19 or other suitable means on a part of the frame of the machine and it is provided with a piston 20 which is connected by a rod 21 to the rocker 12.

An ejector foot 22 is mounted on the end 80 of a rod 23 which carries a piston 24 in the cylinder 25 secured in the head 26. This head is split at 26' to receive a rod 27 upon which the split head is fastened in adjusted position by the set screw 28. The rod 27 is adjustably secured by a set screw 29 in a gage bar 30 which is secured in adjusted position on the machine by a set screw 31. A spring 23' on the piston rod 23 normally holds the 85 ejector foot 22 in retracted position at one side of printing position A and engaging an envelop or other article B on the supporting plate C, Fig. 3^a.

The cylinder 25 is connected by a hose 32 100

with a port slot 33 in the vacuum pump cylinder. A valve chamber 34 at one side of the cylinder 18 has a spring pressed ball valve 35 which engages a seat 36 in a passage 37 leading to the slot 38 at the inner end of the air pump cylinder 18. The ball valve chamber has an exhaust outlet 39. A plunger 40 is guided in a part of the air pump cylinder and is arranged to be operated by the cam end of the arm 14 to unseat the ball valve 35 and permit the vacuum in the cylinder to be relieved through the exhaust port 39. One or more relief openings 41 are provided in the cylinder between the port slot 33 and the outer end of the cylinder.

In one complete cycle of operation of the machine a printing device is fed to printing position, the rocker 12 oscillates, the piston 20 travels inward to a position beyond the port slot 33 and back again, the cam 15 on the arm 14 causes the stamper arm to reciprocate and make an impression from the printing device upon an envelop in printing position, and the vacuum caused by the return movement of the piston 20 operates the ejector piston 24 and the ejector foot, which engages the envelop, to shoot the envelop off to one side of the machine into a receptacle D, Fig. 3^a, in a quick snappy movement, after which the spring 23' returns the ejector foot and the ejector piston quickly to normal retracted position. On the inward stroke of the air piston 20 the air in the cylinder escapes through the relief opening 41 and the passage 37, ball valve chamber 34 and exhaust port 39, and the piston travels to a position between the slots 33 and 38. On the return movement of the air piston 20 the ball valve closes and a vacuum is created within the cylinder which operates as soon as the piston passes the port slot 33 to cause the operation of the ejector foot, as previously described. The port slot 33 is of considerable length to provide an instant opening of suitable area to the suction tube 32 for producing quick operation of the ejector foot. Immediately after the ejector is operated the piston passes the relief hole 41 so that the vacuum is relieved and the spring 23' is permitted to return the ejector piston and foot to normal retracted position. On each return movement of the cam arm 14 the plunger 40 is caused to unseat the ball valve 35 so that the cylinder is always open for the escape of air on the forward stroke of the air piston and when the cam arm moves away from the plunger the pressure created by the forward movement of the piston within the cylinder will be sufficient to hold the ball valve open for the escape of air from the cylinder. But if a printing device is to be skipped the cam arm will not operate and the ball valve will be held unseated by the plunger through the full forward stroke of the piston and also through the full return stroke of the piston

so that no vacuum is created in the air pump cylinder and the ejector will not be operated. The ejector is thus controlled in its operation by the selector mechanism of the machine through its control of the stamper arm in a manner familiar in this type of machine.

The invention is adapted to eject the printed envelop or other article from the machine as soon as the pressure of the platen is removed therefrom so that ample time will be allowed for feeding an envelop into printing position by hand with the machine operating at a relatively high rate of speed. The envelop is registered in printing position against the gage bar 30 and the ejector foot 22 which may be adjusted by the set screws 29 and 31 to accommodate envelops of different sizes and for other purposes. The angular rod 27 for supporting the ejector is secured by the screw 29 in a split socket 29' adjacent one end of the gage bar; and another split socket 42 and adjusting screw 43 are provided at the other end of the gage bar for receiving the angular rod 27 so that the ejector may be arranged on either side of printing position for ejecting the envelop at either side of the machine. To permit this change of position of the ejector the air connection between the pump and the ejector cylinder is made with a flexible hose 32 of sufficient length to reach to either side of the machine.

We have described the invention in a simple form which is suitable for the purpose and which can be easily applied to addressing machines of different constructions now in use as well as to other addressing machines and to folding, sealing and like machines for which it is or may be adapted. Also, we have described the invention as applied to an addressing machine operated by power and provided with selector mechanism, which is now well known in different types or models in commercial use, but it can be used in connection with a pedal or hand operated machine.

We reserve the right to make all such changes in the form, construction and arrangement of parts as fairly fall within the scope of the following claims.

We claim:

1. An ejector for addressing and other machines comprising a reciprocably operated member, a foot to engage the work, and pneumatic means for operating said foot, said pneumatic means comprising a pump cylinder, a piston operating in said cylinder, and means controlled by said member for causing said pneumatic means to operate the foot and eject the work upon the return movement of said member.

2. An ejector for addressing and other machines comprising a selectively operated member, a foot to engage the work, and pneumatic means for operating said foot, said pneumatic means comprising a pump cylinder

der, a piston operating in said cylinder at each cycle of operation of the machine, and means controlled by the operation of said member for causing said pneumatic means to operate the foot and eject the work only when said member operates.

3. An ejector for addressing and other machines comprising a selectively operated member, a foot to engage the work, and pneumatic means for operating said foot, said pneumatic means comprising a pump cylinder, a piston operating in said cylinder at each cycle of operation of the machine, and means controlled by the operation of said member for causing said pneumatic means to operate the foot and eject the work upon the return movement of said member.

4. An ejector for addressing and other machines comprising a reciprocably operated member, a foot to engage the work, and pneumatic means controlled by said member for operating said foot, said pneumatic means comprising a pump cylinder, a piston operating in said cylinder at each cycle of operation of the machine, a valve for permitting escape of air from the cylinder on the forward stroke of the piston, and means for automatically closing said valve to enable the piston to form a vacuum in said cylinder for operating the foot to eject the work.

5. An ejector for addressing and other machines comprising a reciprocably operated member, a foot to engage the work, and pneumatic means for operating said foot, said pneumatic means comprising a pump cylinder, a piston operating in said cylinder, a valve for permitting escape of air from the cylinder on the forward stroke of the piston, and means for closing said valve to enable the piston to form a vacuum in said cylinder for operating the foot to eject the work.

6. An ejector for addressing and other machines comprising a reciprocably operated member, a foot to engage the work, and pneumatic means for operating said foot, said pneumatic means comprising a pump cylinder, a piston operating in said cylinder, a valve held open by said member during the forward stroke of the piston to permit escape of air from the cylinder, and means for closing said valve to permit the piston to form a vacuum in said cylinder when the member operates to cause the foot to eject the work upon the return movement of said member.

55 7. An ejector for addressing and other machines comprising a reciprocably operated member, a foot to engage the work, and pneumatic means for operating said foot, said pneumatic means comprising a pump cylinder, a piston operating in said cylinder, a spring pressed exhaust valve at the head end of the cylinder, a plunger operated by said member for holding said valve open during the forward stroke of the piston and permitting said valve to close when said member

operates for forming a vacuum in said cylinder on the return stroke of the piston, and means intermediate of the foot and the cylinder to cause said foot to be operated by the vacuum in the cylinder to eject the work.

8. An ejector for addressing and other machines comprising a reciprocably operated member, a foot to engage the work, and pneumatic means for operating said foot, said pneumatic means comprising a pump cylinder, a piston operating in said cylinder, means controlled by said member for forming a vacuum in the cylinder only when said member operates, and means intermediate of said foot and said cylinder to cause the foot to be operated by the vacuum in the cylinder to eject the work.

9. An ejector for addressing and other machines comprising a reciprocably operated member, a foot to engage the work, and pneumatic means for operating said foot, said pneumatic means comprising a pump cylinder, a spring pressed valve connected to said cylinder and controlled by said member for permitting exhaust of air from the cylinder upon the forward stroke of the piston and permitting a vacuum to be formed in the cylinder on the return stroke of the piston, a connection between said cylinder and the foot to cause the foot to be operated by the vacuum in the cylinder to eject the work, and said cylinder having an opening to relieve the vacuum in the cylinder immediately after the foot has operated.

10. An ejector for addressing and other machines comprising an operating member, a foot to engage the work, a cylinder, a spring pressed piston operating in said cylinder, a piston rod carrying said foot, and pneumatic means for operating said piston to cause the foot to eject the work.

11. An ejector for addressing and other machines comprising an operating member, a foot to engage the work, a cylinder, a spring pressed piston in said cylinder, a piston rod carrying said foot, and pneumatic means for creating a vacuum in said cylinder to operate the piston and cause the foot to eject the work.

12. An ejector for addressing and other machines comprising an operating member, a foot to engage the work, a cylinder, a spring pressed piston operating in the cylinder, a piston rod carrying the foot, a pump cylinder, a connection between said cylinder and said pump cylinder, a piston operating in said pump cylinder, and means controlled by said member for forming a vacuum in said pump cylinder to cause said foot to operate and eject the work.

13. An ejector for addressing and other machines comprising an ejector foot, a bar adapted to be secured on the machine, clamping means spaced apart on said bar, and a rod for supporting said foot and adapt-

ed to be engaged interchangeably with said clamping means.

14. An ejector for addressing and other machines comprising an ejector foot, a gage bar
5 adjustably mounted on the machine, clamping means spaced apart on said gage bar, and an angular rod adapted to be engaged interchangeably with said clamping means for supporting the foot on either side of
10 printing position.
